Primary Examiner — Keli L Hill*Assistant Examiner* — Sara S Sahneh(74) *Attorney, Agent, or Firm* — Michael Best & Friedrich LLP(57) **CLAIM**

The ornamental design for a balance, as shown and described.

DESCRIPTION

FIG. 1 is a front perspective view of a balance showing our new design according to a first embodiment;

FIG. 2 is a side perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a front perspective view of a balance showing our new design according to a second embodiment;

FIG. 10 is a side perspective view thereof;

FIG. 11 is a right side elevational view thereof;

FIG. 12 is a left side elevational view thereof;

FIG. 13 is a front elevational view thereof;

FIG. 14 is a rear elevational view thereof;

FIG. 15 is a top plan view thereof; and,

FIG. 16 is a bottom plan view thereof.

The broken lines illustrate unclaimed portions of the balance and form no part of the claimed design.
